UNITED STATES PATENT OFFICE.

CONRAD F. LANCASTER, OF EAST LIVERPOOL, OHIO.

ILLUMINATED SIGN.

SPECIFICATION forming part of Letters Patent No. 738,382, dated September 8, 1903.

Application filed October 20, 1902. Serial No. 127,954. (No model.)

To all whom it may concern:

Be it known that I, CONRAD F. LANCASTER, a citizen of the United States, residing at East Liverpool, in the county of Columbiana and State of Ohio, have invented a new and useful Improvement in Illuminated Signs, of which improvement the following is a specification.

My invention relates to illuminated signs; and its object is to provide an improved form of letter for such signs in which fewer lights will be used than are now used.

My invention consists of a novel form of letter hereinafter fully described and claimed.

In the accompanying drawings like characters of reference refer to the same parts throughout both figures.

Figure 1 is a plan view of a letter constructed according to my design. Fig. 2 is a section therethrough on the line 2--2.

The numeral 5 indicates the body of my letter, which is provided with openings therethrough. Through these openings pass lamps 6, preferably illuminated by electric light.

The body 5 of my letter consists of an outer portion 7, formed substantially U-shaped in cross-section, lined internally with a glazed enameled surface 8. Both body portion and enameled surface project within the outline 30 of the letter, as shown at 9.

It is obvious that this enameled surface, being glazed, will act as a strong reflector of the light, and it is equally obvious that, by reason of inwardly-projecting portions 9, the light will be diffused throughout the entire letter in such manner as to illustrate the whole letter equally.

It will thus be seen that I have provided a novel form of letter for illuminating signs in

which the results heretofore specified are accomplished in an economical manner. 40

Minor changes may be made in my invention without materially affecting the principles of the same, and I do not, therefore, desire to confine myself to the exact form herein 45 shown and described, but wish to include all such as properly come within the scope of my invention.

Having thus described my invention, what I claim as new, and desire to secure by Letters 50 Patent, is—

1. An illuminated sign, having a body formed of a frame substantially U-shaped in cross-section, said frame having lamp-receiving openings in the base thereof, lamps provided therein, and inwardly-extending flanges formed integral with the upper edges of the walls of said frame, said flanges adapted to reflect the light inwardly upon the frame, substantially as described. 60

2. An illuminated sign, comprising a frame, substantially U-shaped in cross-section, said frame being lined throughout with a reflecting material, flanges formed at the outer ends of the frame, said flanges bent inwardly at 65 right angles to the walls of the frame and adapted to reflect the light inwardly upon the frame, said frame having lamp-openings in the base thereof, and lamps therein, substantially as described. 70

In testimony whereof I have hereunto signed my name in the presence of two subscribing witnesses.

CONRAD F. LANCASTER.

In presence of—

LOUIS MOESER,
S. B. LEVIS.
